US0D1083707S

(12) **United States Design Patent** (10) Patent No.: **US D1,083,707 S**
(45) Date of Patent: ** Jul. 15, 2025

(54) **AUTOMOBILE HOOD**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **35/519,408**

(22) Filed: **Dec. 20, 2022**

(80) **Hague Agreement Data**

Int. Filing Date: **Dec. 20, 2022**

Int. Reg. No.: **DM/226381**

Int. Reg. Date: **Dec. 20, 2022**

Int. Reg. Pub. Date: **Dec. 22, 2023**

(30) **Foreign Application Priority Data**

Jun. 21, 2022 (WO) WIPO119147
